BED BOTTOM

Dwight E. Austin, Kent, Ohio

Application July 13, 1948, Serial No. 38,400

4 Claims. (Cl. 5—239)

1

This invention relates to bed bottoms and there is disclosed herein more particularly two different types of bed bottoms for use on railway trains and the like and a bed bottom designed more particularly for home use, etc. The different bed bottoms will be separately described and reference will be had to the drawings, in which:

Fig. 1 is an elevation, partly broken away, of a bed bottom designed for use on railway trains and the like;

Fig. 2 is a section, partly broken away, on the line 2—2 of Fig. 1;

Fig. 3 is a view in perspective, partly broken away, of a bed bottom designed particularly for home use, etc.;

Fig. 4 is a view in perspective of a different bed bottom designed for use on railroad trains and the like;

Fig. 5 is a section through one of the elements shown in Fig. 4; and

Fig. 6 is a view in perspective of the element of Fig. 5 rolled up for storage.

Figs. 1 and 2 show an improved bed bottom which utilizes the metal frame now used extensively in rooms and roomettes on Pullman trains. This frame is formed of the metal box having the bottom 1 and sides 2, and a tube or channel such as the tube 3 on all four sides. The usual frame-work does not include the vent holes 6 and 7 or the flange 8 which extends inwardly from the tube 3.

According to this invention sponge-rubber strips 10 are cemented or otherwise fastened to the tops of the tubes 3 and flanges 8. The strips are spaced a short distance in from the sides 2 of the frame. The drawings show the strips off-set inwardly from the inner edges of the tube. The flanges 8 give them the necessary support. Instead of providing flanges on the tubes, plates of the required width may be fastened to the top of them. Any satisfactory support may be used.

A slatted mattress support is provided. The plies 13 and 14 are of canvas or other suitable fabric which may be treated with suitable plastic to render it less pervious. A number of relatively narrow slats 15 are fastened between the fabric plies.

The sponge strips 10 permit the mattress support to give vertically, and also permit lateral give toward the center of the box. Further support is provided by the sponge-rubber blocks 12 which are placed laterally across the box 1. The tops of these sponge-rubber supports are

preferably level with the tops of the sponge-rubber strips 10. In a preferred form of the invention, the sponge-rubber supports 12 are impervious to air so that no air passes through them in either direction. The reason for this will be explained in what follows. To prevent transmission of air through the supports, one or both sides of each support are preferably formed with a skin as is customary in the production of sponge rubber from foamed latex. The slats lie longitudinally of the bed and if they extend its entire length they will be supported at the head and foot by the sponge strips 10. In the preferred form of the invention illustrated in the drawings the slats extend to within a relatively short distance—perhaps a foot, more or less—from the head and foot of the bed and are supported by the strips 12 of sponge and not by the strips 10.

The slats may be of wood or steel or rattan or plastic or aluminum or other metal, etc. They may be one to three inches wide or may be circular or oval, etc. and are spaced a fraction of an inch to an inch or more apart. The fabric 13, 14 is brought over the edge of the box and fastened to the box by rivets 16, but other means for fastening the fabric to the frame may be used. These slats provide a relatively level base for the mattress without permitting enough sag in the longitudinal direction to throw the occupant's back out of line. They provide a hammock effect laterally without causing any great interference with lateral flexing.

The supports 12 divide the box into air pockets or compartments 17 and if these supports and the fabrics 13 and 14 are air-impervious, there is no opportunity for air trapped in them to escape except through the vents or valves 6 provided in each pocket. There may be but one vent 7 through the frame and outer wall of the tube 3 because all of the valves 6 open into the tube 3. The valve means 6 and 7 may be simply small openings or spring valves, etc. may be inserted in them. The valve or valves 7 may be in the side or bottom of the frame. As the train goes over a bump, which tends to quickly elevate the bed bottom, the weight of the occupant will compress the supports 12 and the air will be forced out from the pockets through the valves 6 and 7. The valves regulate the air intake and there is no quick rebound. The tendency of the weight of the occupant to compress the supports 12 when thus jolted is damped by the limited size of the openings with resultant slow expulsion of the air and the tend-

ency to bounce the occupant is practically eliminated because the air returns only slowly. The slats are resiliently supported by the cover fabric 13 and 14 and the supports 12, and the strips 10 along the sides of the frame give laterally inwardly as weight is applied. The effect of such support is to cushion the jolting which the occupant of a railroad bed is accustomed to experience.

A mattress of any construction will be laid over the slatted cover. A thin sponge-rubber mattress will give satisfaction. The bed thus comprises, in addition to the mattress, a bed bottom which utilizes the metal frame now in wide use in railroad cars, with the slatted cover supported on all four sides by resilient cushions 10. An important feature of the invention is the substantially air-impervious resilient supports 12 which, when cemented to the bottom of the box and also to the cover, divide the contents of the frame laterally into air pockets 17. These air pockets may be suitably valved to provide equal expulsion and intake of air, to permit rapid expulsion of the air with only slow return, or to permit slow expulsion with rapid return. For example, the frame may be provided with additional openings valved to permit only the outward or inward flow of air. Valves of any desired construction and number may be provided to regulate the inflow and outflow of air in any desired manner.

The tubes may measure about two inches and a half in each direction, and the strips 10 may be an inch and a half thick, giving a total weight of about four inches to the bed bottom. The supports 12 may be some three or four inches wide and in a bed bottom of the dimensions given, the supports will ordinarily be four inches high. The strips 10 are cemented to the tubes 3 and flanges 8. A bed bottom of such construction with a relatively thin mattress has been found to give an exceptionally comfortable ride on even a bad road-bed.

The bed bottom of Fig. 3 is designed particularly for use in the home but may be utilized elsewhere. It comprises a bottom support 26, which may be of any usual construction and may be slatted or solid. A solid wooden bottom with wooden sides 21 will be found satisfactory. Bed springs 22 cover this bottom. Each spring may be enclosed in a canvas cover 23 or the cover may be omitted. Fig. 3 shows the springs supported on a canvas or other suitable fabric bottom sheet 24, with side sheets 25 of the same material. The top 26 of the over-all spring enclosure is formed of two plies of fabric 28 with slats 29 positioned between them. These slats may be of the same general construction as those mentioned in connection with Figs. 1 and 2, with modifications there suggested. They need not extend to the head and foot of the bed as shown, but may stop some nine to twelve inches of this at each end. They may be spaced less than an inch apart up to several inches apart. This slatted cover 26 is supported by the springs 22, and may be suitably united to the side fabrics 25 by piping 27 which may include suitable cord material or the like.

This bed bottom fits into an ordinary bedstead. When covered by a mattress of any type it forms a resilient and cushioned support in which the slats serve to form a relatively flat base with sufficient flexibility longitudinally for comfort but without sufficient longitudinal flexibility to permit the occupant's back to be thrown out of

line. The separated slats give a lateral hammock-effect.

Figs. 4, 5 and 6 illustrate another type of bed bottom designed particularly for use on railroad trains and the like. It may be quickly disassembled and is easily stored. It is formed of the two sponge-rubber mattresses 40 and 41. These are separated by the slatted-fabric support formed of slats 42 held between two fabric covers 43 and 44. These slats may be of the same general construction as those hereinbefore described and may be similarly spaced between the fabric plies 43 and 44. The sponge-rubber mattresses will preferably be well cored, as at 45, to form a soft support. The bottom mattress 40 may simply be laid on a floor or, if used on a train, will be placed on a support formed between two adjoining seats, or it may be used in any other suitable manner. No retaining sidewalls are required, but may be used.

The slatted fabric provides a relatively level supporting medium and with the slats lying longitudinally of the bed, gives flexibility without permitting the occupant's back to be thrown out of line. The slatted fabric limits the extent to which the sponge will give outwardly when a weight is supported on it, thus forming a relatively thick mattress of high lateral stability. When the bed is not in use, the sponge-rubber mattresses may be stored or used for any purpose and the slatted fabric may be rolled as indicated in Fig. 6 and stored in any convenient small storage space. Alternately, the two mattresses and slatted support may all be sewed into a suitable outer cover. Each of the mattresses 40 and 41 may be made up of smaller units such as seat backs, etc., as may be convenient on a train. The bottom mattress need not extend the whole length of the slatted cover, but may be formed of a number of pieces rather widely spaced.

Alternatively, using an ordinary bed bottom or springs, and an ordinary mattress, which may be of sponge rubber, hair, etc., the slats may be made a part of the lower cover of the mattress.

The use of narrowly-spaced slats running longitudinally of the bed, with the slats which are slightly flexible fastened in or to a cover member supported at all four edges to give inwardly, or otherwise as described forms a highly desirable mattress support. Details of the construction illustrated may be varied without departing from the scope of the invention as defined in the claims.

What I claim is:

1. A bed bottom which comprises a box member with support extending inwardly from all four walls thereof; a resilient member on each of these supports, flexible slats extending longitudinally of the bed bottom, the slats being joined laterally by flexible means which is connected with the sidewalls of the box support to maintain them in place and is supported by said resilient members, and at least one resilient support for each slat intermediate the head and foot thereof.

2. A bed bottom which comprises a rectangular support which has substantially the same area as the desired bed, a narrow resilient cushion supported by each wall of said rectangular support, a flexible cover member with flexible slats fastened thereto, each of the slats extending longitudinally of said rectangular support, resilient supporting means supporting each slat intermediate its ends, the cover member being supported along each side of the bed bottom by the resilient cushions supported by the side walls of the rectangular support.

3. A bed bottom which comprises a metal base with metal sides extending upwardly therefrom, sponge-rubber supports on the interior of each of the four walls of the bed bottom extending the length of each of the walls, a substantially air-tight cover member formed with closely-spaced, flexible slats extending longitudinally of the bed bottom, with the sides of the cover member supported by the side sponge-rubber supports, located transversely of the bed bottom sponge-rubber cushions resting on said base and supporting the slatted cover at spaced intervals intermediate the head and foot of the bed bottom, said transverse sponge-rubber cushions being substantially air-impervious and dividing the bed bottom into substantially air-tight compartments, the said base and side members of the bed bottom being substantially air-impervious except for valve means controlling the flow of air into and out of each of said compartments.

4. A bed with a head, a foot and two sides therebetween, which comprises a frame substantially outlining the periphery thereof, supports extending inwardly from portions of the frame at the head, the foot and both sides of the bed,

a resilient member on each support, flexible slats extending longitudinally of the bed, the slats being joined laterally by flexible means which is connected with the sides of the frame to maintain them in place and is supported on said resilient members at the sides of the frame, and at least one resilient support for each slat intermediate its head and foot.
